COUNTER TOP DISPLAY PARTITION

David M. Moore, Pittsburgh, Pa., assignor to Armstrong
Store Fixture Corporation, Pittsburgh, Pa.

Filed Mar. 5, 1973, Ser. No. 338,315

Term of patent 14 years

Int. Cl. D6—06

U.S. Cl. D6—193

FIG. 1 is a perspective view of a counter top display partition showing my new design;

FIG. 2 is a side elevational view thereof; and

FIG. 3 is a side elevational view showing a modified form of my new design.

I claim:

The ornamental design for a counter top display partition, as shown and described.
